HONING

Theodore A. Olson, Pompton Plains, N. J., assignor
to General Motors Corporation, Detroit, Mich.,
a corporation of Delaware

Application January 2, 1947, Serial No. 719,886

7 Claims. (Cl. 51—59)

1

This invention relates to honing and comprises all the features of novelty herein disclosed. An object of the invention is to provide an improved method of honing, as by use of a hone which always starts the honing with a ridge or high spot at high unit pressure and ends with an area of contact at lower unit pressure. Another object is to provide improved apparatus for effecting a honing operation with great efficiency, as by indexing a honing wheel after an area has worn into it and so always presenting a new high spot or ridge to start each new honing operation. To these ends and also to improve generally upon honing methods and apparatus, the invention consists in the various methods hereinafter described and claimed. In its broader aspects, the invention is not necessarily limited to the construction selected for illustrative purposes in the accompanying drawings in which:

Fig. 1 is a front view of a portion of the apparatus with some parts in section;

Fig. 2 is a plan view of some of the elements of Fig. 1;

Fig. 3 is a sectional view of the mechanism for reciprocating the hone;

Fig. 4 is a side view of the apparatus to smaller scale;

Fig. 5 is a diagrammatic plan view of the work supporting and rotating means;

Fig. 6 is a plan view of a pawl-carrying arm.

In this apparatus, a honing wheel or disc is rapidly reciprocated without any rotation against a rotatably driven work piece and, at the conclusion of the honing operation, is withdrawn from the work and indexed circumferentially by a ratchet mechanism prior to advance into honing relation to a new work piece. The wheel initially has a line contact with each work piece for rapid honing and acquires a gradually increasing area of contact as it breaks down and conforms to the work surface. Thus the pressure per unit of area is higher to begin with and decreases and becomes a glazed area which, though suitable for finishing, would be unsuitable to begin operation on a new work piece. The indexing movement is less than the angular extent of the glazed area so that the wheel presents a line of contact with each new work piece for rapid initial honing. The wheel acquires a polygonal appearance although the sides are not flat (unless the work is flat) but are curved when the work is circular. In any case a new high spot or ridge becomes available to begin honing on each new work piece.

In the drawings, a support 2 supports a cylinder 4 having a piston rod 6 which is provided with an

overhanging arm 8 secured to the forked upper end of a slide or carrier 10 which is guided in bearings in the support 2. The slide or support carries the honing mechanism and is given one reciprocation at each cycle, as to bring the hone into working relation with the work and to remove it therefrom. Reciprocating within the slide or carrier 10 is a honing shaft or plunger 12 which is connected by a link 14 and a bushing 16 to the eccentric portion of a rotating shaft 18. The shaft is journaled by bushings in the forked upper end of the slide or carrier 10 and is rapidly driven by a belt pulley 20, thus giving the honing disc or wheel H a rapid reciprocation.

Removably secured to the lower end of the shaft or plunger 12 by a set screw (or integral with it if desired) is a cupped member 26 having a peripheral flange 28 on which a ratchet ring 30 is supported by its internal flange 32. A felt sealing ring 33 seals the joint. The ratchet ring has a downwardly projecting annular rib 34 which is very slightly thicker than the flange 28. Fastened to the ratchet ring by dowel pins 36 and screws 38 is an outwardly projecting flange 40 on an adapter or wheel holder 42 to which the honing wheel H is clamped by a screw. The holder 42 is journaled for circumferential indexing on a bushing carried by a cylindrical projection 44 of the member 26. To prevent undesired turning, brake shoes 46 are urged against the member 26 by coil springs 48 housed in the holder 42.

A ring 50 having an arm 52 is journaled for oscillation around the annular rib 34, the ring being slightly thinner than the rib for running clearance while supported on the flange 40. The arm 52 carries a pivoted pawl 54 urged by a spring 56 against the ratchet ring, a stop pin 58 limiting pivotal movement. The pawl-carrying arm 52 is urged by a coil spring 60 against an inclined cam 62 on a bent plate 64 attached to the support 2. The spring 60 is attached to a post on arm 52 and to a bent arm 66 having an arcuate portion 68 attached to the member 26, the arm 66 having an adjustable stop screw 70 to limit movement of the pawl carrying arm in one direction. The arm is urged in one direction by the spring and is moved in the opposite direction when it rides up the cam.

Any suitable means (such as shown in detail in Hutchinson, Serial No. 570,110 Patent 2,433,455) is provided for supporting and rotating the work ring W. Hardened blades 72 engage the bottom edge of the work, a pair of driven rollers 74 engage the periphery, and a pressure roller 76 urges the work against the driven rollers. Any suitable

means is used to cause relative feeding movement between the honing wheel and the work, as by feeding the wheel radially of the work in the direction of the arrow in Fig. 5. The honing wheel will first engage the work with line contact and then will break down into an increasing area 80 conforming to the work. When the entire honing mechanism is lifted from the work by action of the cylinder 4, the arm 52 engages the cam and causes the honing wheel to be indexed by a small amount which is less than the angular extent of a worn face 80. Hence, in the subsequent descent of the honing mechanism one of the ridges 78 is in position for line contact with the work at a high unit pressure which gradually decreases. As the operation is repeated again and again, the wheel acquires a polygonal appearance and so long as a new work surface is placed in the same location as the first work surface, a ridge will always be available for the initial line contact and the honing cannot begin with an area of contact.

I claim:

1. In apparatus of the character indicated, a reciprocating plunger, a wheel holder mounted for circumferential indexing movement with respect to the plunger, a honing wheel secured to the holder, a ratchet mechanism supported by the plunger, a shiftable carrier for the foregoing parts, a support for guiding the carrier, a cam on the support, and means for shifting the carrier to cause the cam to operate the ratchet mechanism.

2. In apparatus of the character indicated, a reciprocating plunger, a wheel holder mounted on the plunger for circumferential indexing movement with respect to the plunger, a honing wheel secured to the holder, means for reciprocating the plunger to carry the honing wheel along a work surface, means for moving the wheel out of engagement with the work surface, mechanism for indexing the wheel a distance less than the angular extent of the area worn on the wheel, and means for moving the wheel into engagement with a work surface at the same location as the first.

3. In apparatus of the character indicated, a reciprocating plunger, a wheel holder mounted for indexing movement with respect to the plunger, a honing wheel secured to the holder, a ratchet secured to the holder, an arm rockable with respect to the holder, a pawl on the arm and engaging the ratchet, a shiftable carrier for all of the foregoing parts, a support for guiding the carrier, a cam on the support, and means for shifting the carrier to cause the arm to react with the cam and index the wheel.

4. In apparatus of the character indicated, a reciprocating plunger, a wheel holder reciprocating with the plunger and mounted for indexing movement with respect to the plunger, a honing

wheel secured to the holder, means for preventing rotation of the wheel while reciprocating along a work surface, means for separating the wheel and the work surface, and means for indexing the wheel and its holder while the wheel and work surface are separated.

5. In apparatus of the character indicated, a support, a carrier guided by the support, means for sliding the carrier, a plunger guided by the carrier, means for reciprocating the plunger, a honing wheel mounted on the plunger, a ratchet wheel having connection with the wheel, a pawl-carrying member journaled for turning movement with respect to the plunger, a cam fixed to the support, and means for sliding the carrier with respect to the cam to cause the pawl carrying arm to react on the cam to index the honing wheel with respect to the plunger.

6. In apparatus of the character indicated, a reciprocating member, a hone holder journaled on the reciprocating member for circumferential indexing movement, a honing member secured to the holder, a carrier to guide the reciprocating member, a support for guiding the carrier, means for shifting the carrier with respect to the support to carry the honing member into and out of operative relation to a work piece, a cam secured to the support, an arm journaled for angular movement on the reciprocating member adjacent to the hone holder, a one-way turning connection between the arm and the hone holder, and the cam being mounted in the path of the arm to turn the latter as the carrier is given its shifting movement.

7. In apparatus of the character indicated, a reciprocating member, a hone holder journaled on the reciprocating member for circumferential indexing movement, a honing member secured to the holder, a carrier to guide the reciprocating member in its reciprocation, a support for guiding the carrier in the direction of said reciprocation, means for shifting the carrier with respect to the support to carry the honing member into and out of operative relation to a work piece, and means controlled by said shifting movement to cause the hone holder to index circumferentially with respect to the reciprocating member.
